UNITED STATES PATENT OFFICE.

ELIJAH J. B. WHITAKER, OF NEW YORK, N. Y

SWINGING DOOR.

No. 839,686.

Specification of Letters Patent.

Patented Dec. 25, 1906.

Application filed November 6, 1903. Serial No. 180,032.

To all whom it may concern:

Be it known that I, ELIJAH J. B. WHITAKER, a citizen of the United States of America, and a resident of the borough of Manhattan, in the city of New York, State of New York, have invented certain new and useful Improvements in Swinging Doors, of which the following is a specification:

This invention relates to improvements in swinging doors, and especially such as are designed to be put in storm-houses, vestibules of buildings, and other places where doors are exposed to the force of the wind.

My invention consists, essentially, in the combination of a plurality of swinging doors arranged to open in opposite directions with an operative connection from one door to the other, whereby the opening of one door opens the other door in the opposite direction, and on one or both of the doors I may place the usual door-closing spring and door-check.

The doors are adapted and constructed to be opened easily merely by a person pressing against either of them and without requiring the person to operate any levers, gears, pulley-cords, or other contrivances, which are impracticable in the circumstances in which the doors are generally used—that is, in buildings in large cities, where great numbers of people pass through the doors in a very short time, and such contrivances as just mentioned would delay the opening of the doors and render their operation so awkward to persons in a hurry as would result in blocking the hallways of the buildings.

By this invention, since the two doors are of the same size and shape, the wind-pressure on both doors is equal and counterbalances itself, so that I can dispense with the usual powerful closing-spring, which is made strong enough to close the door against a strong wind, and consequently renders the door very difficult to open in still weather and can use only a light closing-spring, just sufficient to swing the doors to and which opposes very little resistance to opening the doors. Each door is also arranged to open only in one direction. In this country, where the practice is for persons to keep to the right, each door is arranged to open only on the right, so as to force people who wish to pass through to keep to the right, which is a great advantage in commercial buildings in large cities, for it prevents the throngs of people going into and out of the building from interfering with each other.

Other features of the invention are explained in the specification, referring to the accompanying drawings, in which—

Figure 1 is an elevation of a pair of swinging doors arranged according to my invention as seen from the inside, the doors being closed. Fig. 2 is a view of the same from above, but with the doors partly opened; and Fig. 3 is a horizontal sectional view, partly broken, of the closed doors to show the catches at the astragal moldings.

The door-casing 1 should preferably be set in a vestibule, storm-house, or other situation in which the swinging doors 2 3 will be within the outer walls of the building or within such storm-house or like structure, as is clearly indicated in Fig. 2, where the doors are shown as situated in a vestibule 4, and said door-casing 1 is rabbeted at 5 6 to cover the edges of the doors 2 3 and prevent the wind blowing through when said doors are closed. Said doors 2 3 are respectively hinged, as at 8 9, on opposite sides, so as to open only in opposite directions, Fig. 2, and are so arranged as to respectively permit those persons to pass through only to the right where it is the custom to keep to the right.

Should the doors be erected in localities where it is the custom to keep to the left, they would be hinged in the reverse manner and so as to let persons pass through only to the left. At the meeting edges, but respectively on opposite sides, each of said doors 2 and 3 is provided with astragal moldings 12 13, which serve both as weather-strips and as stops to the other door, the astragal molding of one door becoming, in effect, when the doors are closed a door-post for the other door and preventing the pushing of either door in the wrong direction, as will be hereinafter further explained. About midway of the height of each door is a catch 16 17, respectively arranged to engage a corresponding socket 18 19 in the other door. If an attempt is made to open the doors in the wrong direction, said catches grip in their respective sockets and aid in preventing opening the doors. At the top of each said door 2 and 3 are firmly secured arms 22 23, respectively, and said arms are preferably positioned so that the line joining the pintles of their respective hinges and said arms make angles of substantially forty-five degrees with the plane of the doors. Thus the line-joining pintle of hinge 8 and the arm 22 and also the line-joining pintle of hinge 9 and the arm 23 in Fig. 3 each makes

an angle of about forty-five degrees with the plane of the doors, for I find this is the most advantageous position of said arms 22 23 for effecting the easy opening of the doors. Said arms 22 23 are connected by a pivotal connecting-rod 25, positioned on each rod 22 23 between the shoulders 26 and cotter-pins 27. To facilitate adjustment, said rod 25 is preferably provided with threaded sleeves 28 29, having eyes which fit over said arms 22 23.

In order to render the doors self-closing, I prefer to place on one of them any of the usual door-closing springs or combined springs and checks; but by reason of wind-pressure on one door balancing that on the other I am able to use much weaker door-closing devices than are now necessary, and I can use such as offer but little resistance to opening the doors. In the drawings I have indicated one of the doors provided with a very common form of door spring and check 30 and can of course use any other kind and can, if desired, place a door-closing device on each door. I also prefer to attach to each door about midway of its height a tape or chain of suitable material, the other end of which is wound in an ordinary tape-spring barrel 33, fixed to the walls or partitions so as to make an angle of about forty-five degrees with the plane of the doors. Said tape or chain 32 and barrel 33 are similar in construction to the well-known spring measuring-tapes and cases and require no further description. The purpose of said chain or tape 32 is to guard the corner-spaces on the side toward which the doors 2 3 respectively open to prevent people from standing in said corners in the way of the doors, and thus also 40 keep pedestrians to the right.

As will be clearly understood from the foregoing description, a person wishing to pass through the doors, say, to the right of Fig. 2, pushes against door 3, which opens easily, 45 because in whatever direction the wind may be blowing the wind-pressure, if any, tending to keep door 3 closed, is counterbalanced by the wind-pressure tending to open door 2, the wind-pressure on one door being communicated to the other door through the rod 25. Now the person opens door 3 to pass through,

thereby also opening door 2. As he opens said doors the said chains 32 wind up into their casings. Then, as he passes through, the door-spring 30, being strong enough to overcome the extremely weak springs of the said chains or tapes, swings the doors closed again. It is manifest that any attempt to open a door in the wrong direction presses the other door against it, so that the moldings 12 or 13 60 and catches 16 or 17 prevent the opening of said door in such wrong direction.

I am aware that doors have heretofore been constructed to open in opposite directions through the agency of gear-trains, levers, and other mechanical devices operated by cars as they pass by, also that gates have been constructed to be operated by persons pulling or in some other manner actuating cords, levers, and the like, whereby motion is 70 ultimately transmitted to the gate, and I do not desire to claim any such constructions, since my doors are operated directly by the persons pressing against them without the aid of such contrivances.

Now, having described my improvements, I claim as my invention—

The combination with a vestibule of solid double weather and wind excluding doors pivoted at their outer edges at a distance 80 within the entrance of said vestibule at least equal to the width of one door, and provided with lapping means at their meeting edges so that one door may only swing inwardly and the other door outwardly, a rod operatively 85 connected to one door within and to the other door outside of its line of pivoting, so that the movement of either door in its permissible direction moves the other door in its permissible direction, whereby the wind-pressure entering said vestibule can act only substantially normal to the said double doors and the pressure of the wind on one door is neutralized by its pressure on the other door without interfering with the opening or closing of either door, substantially as described.

Signed at New York city this 4th day of November, 1903.

ELIJAH J. B. WHITAKER.
